UNITED STATES PATENT OFFICE

1,982,753

REVERSIBLE WINDOW

Elmore Henry Panter, Louisville, Ky.

Application May 2, 1933, Serial No. 669,003

1 Claim. (Cl. 20—48)

The present invention relates to a window having a double sash frame one rockable in the other so that the inner frame may be reversed and the object of the invention resides in the provision of weatherproof means for holding the frames in normal position yet permitting one frame to be rocked with respect to the other.

Another very important object of the invention resides in the provision of a reversible window of this nature which is simple in its construction, inexpensive to manufacture, strong and durable, easy to manipulate, thoroughly efficient and reliable in use and otherwise well adapted to the purpose for which it is designed.

With the above and numerous other objects in view as will appear as the description proceeds, the invention consists in certain novel features of construction, and in the combination and arrangement of parts as will be hereinafter 20 more fully described and claimed.

In the drawings:

Figure 1 is an elevation of a window sash constructed in accordance with my invention showing a portion in section.

Figure 2 is a horizontal section taken substantially on the line 2—2 of Figure 1.

Figure 3 is a vertical section taken substantially on the line 3—3 of Figure 1, and

Figure 4 is an enlarged detail section through 30 one rail of the sash.

Referring to the drawings in detail it will be seen that the sash comprises an outer frame 5 and an inner frame 6. The rails of the outer frame 5 are hollow and on their inner faces are 35 provided with longitudinally extending slots 7. Tongues or strips 8 are mounted in said hollow rails of the frame 5 and have formed thereon beads 9 projectable through the slots 7 for engagement in grooves 10 provided on the outer 40 faces of the rails of the frame 6. Springs 11 are mounted in the rails of the frame 5 to impinge against the strips 9 for normally urging the beads into engagement with the grooves 10. The frame 6 is provided with a pair of trunnions 14 45 on opposite sides thereof and journalled in the

frame 5 so that the inner frame may be rocked and reversed with respect to the outer frame. The glass pane or the like 15, of course, is mounted in the inner frame 6 in any suitable manner.

It is thought that the construction, operation, utility and advantages of this invention will now be quite apparent to those skilled in this art without a more detailed description thereof.

The present embodiment of the invention has been described in considerable detail merely for the purposes of exemplification since in actual practice it attains the features of advantage enumerated as desirable in the statement of the invention and the above description.

It will be apparent that changes in the details of construction, and in the combination and arrangement of parts may be resorted to without departing from the spirit or scope of the invention as hereinafter claimed or sacrificing any 75 of its advantages.

Having thus described my invention, what I claim as new is:

In a reversible window, a sash including an outer frame and an inner frame pivoted within said outer frame; each frame having the sides thereof integral one with the other at the corners of the frame, said outer frame having each of its sides hollow, and each of said sides having a slot on its inner face, a thin flat strip housed within each of the said sides of the outer frame and provided on one face thereof with a bead projectable through said slot, springs arranged in the hollows of the said sides of the 80 said outer frame and engaging said strips for yieldably retaining said strips against the slotted faces of said sides, and said inner frame having on the inner faces of its sides grooves with which said beads are engaged for releasably retaining the inner frame against swinging 90 movement and to provide a weatherproof joint between corresponding sides of the inner and outer frames.

ELMORE HENRY PANTER.
